US0D1049081S

(12) **United States Design Patent** (10) **Patent No.:** **US D1,049,081 S**
(45) **Date of Patent:** **** Oct. 29, 2024**

(54) **TELEVISION RECEIVER**

(71) Applicant: **LG ELECTRONICS INC.**, Seoul (KR)

(72) Inventors: **Yongseok Kim**, Seoul (KR); **Jiwon Park**, Seoul (KR)

(73) Assignee: **LG ELECTRONICS INC.**, Seoul (KR)

(**) Term: **15 Years**

(21) Appl. No.: **35/519,269**

(22) Filed: **Nov. 10, 2023**

(80) **Hague Agreement Data**

Int. Filing Date: **Nov. 10, 2023**

Int. Reg. No.: **DM/233413**

Int. Reg. Date: **Nov. 10, 2023**

Int. Reg. Pub. Date: **Dec. 8, 2023**

(30) **Foreign Application Priority Data**

Jun. 20, 2023 (KR) 30-2023-0023563

(51) **LOC (14) Cl.** **14-03**

(52) **U.S. Cl.**
USPC **D14/223**
